UNITED STATES PATENT OFFICE.

HEINRICH BESANCON, OF BIENNE, SWITZERLAND.

RAZOR.

1,326,635.

Specification of Letters Patent.

Patented Dec. 30, 1919.

Application filed January 30, 1919. Serial No. 274,089.

To all whom it may concern:

Be it known that I, HEINRICH BESANCON, a citizen of Germany, residing at Bienne, Canton of Berne, Switzerland, have invented new and useful Improvements in Razors, of which the following is a specification.

The subject of the present invention is a razor in which a steel lamina forming the 10 razor blade is held between clamping jaws of a blade holder. The feature of the device is that the clamping jaws are formed by the ends of a folded resilient metal strip.

One embodiment of the invention is illustrated in the accompanying drawing in which Figure 1 is a plan view and Fig. 2 a section on the line A—B of Fig. 1.

In the embodiment shown the blade holder consists of the folded resilient metal 20 strip *a*. The latter has two limbs *a'* *a''*, the ends *b*, *b'* of which form the clamping jaws between which the razor blade *d* is arranged and clamped. As shown in Fig. 2, the strip or plate is so bent that the cylindrical portion *a* is out of symmetry with the jaws; that is to say, a larger portion of such cylindrical portion is at one side of the pair of jaws than at the other side. The upper clamping jaw is fitted with three 30 studs *c* adapted to pass through the blade *d* formed of a thin steel lamina, and through corresponding openings in the lower clamping jaw. The central stud *c* is screw threaded and fitted with a nut *e*. By 35 tightening the latter the clamping jaws are brought together, clamping the blade *d* in position. If the nut is loosened back the

clamping jaws separate from one another, and the blade can then be removed from the holder. The lower clamping jaw is 40 formed with comb-like teeth at its free end while the upper clamping jaw is slightly arched; the lower jaw may be arched similarly to the upper in such manner that the blade when clamped may be correspond- 45 ingly bent, and thus more firmly held.

Having now particularly described and ascertained the nature of my said invention and in what manner the same is to be performed, I declare that what I claim is: 50

A razor comprising a resilient plate bent upon itself to form a pair of jaws, one of said jaws lying in a horizontal plane and having a plurality of openings therein, and the other jaw curved away therefrom and 55 provided with a plurality of studs adapted to pass through said openings, a cylindrical portion immediately back of said jaws and out of symmetry therewith, a blade adapted to be clamped between said jaws and pro- 60 vided with a plurality of openings adapted to register with the openings in the horizontal jaw, one of said studs being threaded, and a nut adapted to fit said threaded stud for closing the jaws together and adjust- 65 ing the horizontal jaw and the blade toward the curvature of the other jaw.

In testimony whereof I have signed my name to this specification.

BESANCON, HEINR.
